Filed Apr. 17, 1964, Ser. No. 79,560

Term of patent 14 years

(Cl. D26—1)

Fig. 1.

Fig. 2.

Fig. 3.

FIG. 1 is a side elevation of an electrode for measuring dissolved oxygen or the like showing my new design;

FIG. 2 is a top plan view thereof; and

FIG. 3 is a bottom plan view thereof.

The side not shown is essentially a mirror image of the side illustrated in FIG. 1.

The drawing is shaded to indicate contrast in appearance.

I claim:

The ornamental design for an electrode for measuring dissolved oxygen or the like, substantially as shown and described.
